FURNACE

Max C. Richardson, Portland, Oreg., assignor to
 Iron Fireman Manufacturing Company, Portland, Oreg.

Application June 15, 1938, Serial No. 213,829

2 Claims. (Cl. 126—99)

This invention relates generally to heating appliances, and particularly to a warm air furnace.

The main object of this invention is to construct a furnace in which the body and radiator portions are in the form of aerofoils for the purpose of reducing the resistance to the flow of air therethrough.

The second object is to so construct a furnace and its component parts that the air passing therethrough will wipe heat therefrom without producing pockets or setting up a turbulent action.

The third object is to so construct a furnace that all of the hot gases produced within the furnace will pass through the various radiator elements in series.

The fourth object is to so construct a furnace that it will have sufficient radiating surfaces for heat and relatively large gas passageways in order that accumulations of fly ash will not impair its efficiency.

The fifth object is to so construct a furnace that incombustibles remaining in the furnace can be put into an ash can which is disposed within the furnace itself.

The sixth object is to so construct a furnace as to especially adapt it for use in connection with a stoker in which the retort is disposed between the coal bin and the stoker drive mechanism and in which the stoker is contained within the furnace itself.

The seventh object is to construct a furnace in a manner that stokers may be disposed therein in any one of several positions to better adapt it to the requirements of a given installation.

The eighth object is to construct an improved form of furnace which is relatively easy to manufacture and which will extract heat from the burned gases at a substantially uniform rate across its entire heat transferring area.

The ninth object is to construct a furnace of the class described which is readily interchangeable for use in connection with a stoker for solid fuel or for use in connection with oil burning equipment.

These and other objects are accomplished in the manner set forth in the following specification as illustrated in the accompanying drawings, in which:

Fig. 1 is a plan view of the furnace showing its relation to a coal bin and chimney.

Fig. 2 is a vertical section taken along the line 2—2 in Fig. 1.

Fig. 3 is a vertical section taken along the line 3—3 in Fig. 2.

Fig. 4 is a section taken along the line 4—4 in Fig. 3.

Fig. 5 is a horizontal section taken along the line 5—5 in Fig. 2.

Fig. 6 is a fragmentary vertical section showing a modified use of the device in connection with an oil burner.

Similar numerals refer to similar parts throughout the several views.

Referring in detail to the drawings, there is shown a base 10 around which are constructed the upright side walls 11 and 12 and the end walls 13 and 14. The end walls 13 and 14 connect with the sloping portions 15 of the casing hood whose edges 16 are upturned.

Within the furnace and spaced above the base 10 are the combustion chamber walls 17 which converge toward the ridge 18 which is substantially along one center line of the furnace. The lower ends 19 of the walls 17 are curved inwardly toward the bottom 20 which is provided with a circular flanged opening 21 into which extends the retort base 22 of a coal burning stoker. The cast iron fire pot liner 23 is placed around the inner side of the curved portion 19 as shown in Fig. 3.

The combustion chamber walls 17 and the curved portion 19 are closed by means of the ends 24 and 25, the latter of which has an opening 26 formed therein which is connected by means of a flange 27 with the fire door opening 28 of the furnace. The opening 28 is provided with a fire door 29 which may be of any convenient type. The bottom 30 of the flanged member 27 is provided with a flanged opening 31 through which ashes may pass into the ash can 32 which is disposed on the under side of the bottom 30. The combustion chamber walls 17 are supported by the upright legs 33 which rest upon the base 10.

Liners 34, 35 and 36 are spaced from the walls 11, 12, 13 and 14 for the purpose of preventing heat from reaching the outer walls 10 to 16, inclusive.

On opposite sides of the combustion chamber walls 17 are disposed the streamlined radiators 37 and 38, the former of which is connected by means of a flanged smoke collar 29 with the wall 17, whereas the radiator 38 is connected by means of the transverse duct 40 with the radiator 37. It will be noted that the lower side 41 of the transverse duct 40 extends well below the top of the smoke outlet opening 42 which is joined by the smoke pipe 43 to the chimney 44. It is desirable to provide clean-out openings 45

for the radiators 37 and 38 and to provide easily removable caps 46 therefor.

It will be noted that the walls 17 of the combustion chamber converge slightly with relation to the walls 47 of the radiators 37 and 38 permitting an easy flow of air therethrough for accommodating the passageway to the increased volume caused by the rising temperature of the air passing therethrough.

The retort base 22 has connected thereto a coal feeding tube 48 which contains a coal feeding worm 49 which extends into the coal bin 50. The worm 49 extends through the retort 51 which is formed within the retort base 22 and thence into the tube 52 from whence its shaft 53 connects with the transmission contained within the housing 54. An electric motor 55 furnishes the power to drive the shaft 53 and also the fan contained within the casing 56 which delivers air into the retort base 22 through the air duct 57. The retort 51 is provided with slots 58 through which air can escape from the plenum chamber 59 to which it is delivered through the duct 57.

In the form of the device shown in Fig. 6, an oil burner 60 is disposed within the compartment 61 which formerly held the housing 54 of the stoker. In this form of the device, it is desirable to provide a fire pot 62 of a refractory material which is preferably confined within a metallic container 63. A trough 64 is formed around the container 63 and it is used to form a seal between the members 63 and 49. A sealing composition 65 is placed in the trough 64. An air intake pipe 66 delivers cold air through the wall 62.

It can be seen from the foregoing that I have provided a furnace which possesses a number of desirable characteristics inasmuch as it is self contained and has incorporated therein either a coal burning stoker or an oil burner which may occupy various positions with relation to the furnace.

It will also be noted that when a coal burning stoker is employed that clinkers may be picked out of the retort 51 with suitable tongs and dropped through the opening 34 into the ash can 32 without moving the clinkers out of the furnace proper so that any dust which rises from the clinker removing operation will be carried out through the smoke pipe 43 instead of escaping into the furnace room.

Special attention is called to the fact that there is a natural flow of air through passages of increasing dimensions across which passageways heat is conducted and reflected in the path of the air currents, the net result of which is very uniform heating of the various radiator elements which not only adds to the life thereof but also avoids the overheating of any portion of the air.

Openings 67 are formed in the walls 13 and 14 and provided with the closures 68 and 69, the latter of which is provided with a packed

flange 70 which surrounds the coal feeding tube 48.

When the oil burner 60 is used instead of the coal burning stoker, the closure 69 is replaced by a closure 71.

It is also desirable to provide the casing 61 with a packed flange 72 which either surrounds the tube 52 of the coal burner or the tube 73 of the oil burner 60.

10 It can be seen from the foregoing that with this arrangement, the oil burner 60 can be placed in any one of three positions while when the coal burning stoker is employed, it can be set in either one of two positions.

15 It will also be seen that as heat is radiated from the walls 17, it is conducted by the walls 47 back into the air stream in a form which permits it to be picked up by the passing air current.

20 Obviously, this is also true of heat which is radiated outwardly against the reflecting liner 36.

It will also be noted that baffle plates may be placed between the members 17 and 47 as well as between the outer sides of the members 25 37 and the liner 36 without departing from the spirit of this invention.

It will be noted that by making the radiators in the form of aerofoils, the resistance to the flow of air through the furnace is reduced to a minimum.

I claim:

1. A furnace having in combination a retort, an elongated fire box disposed over said retort, straight converging sides forming an elongated

35 ridge, a hollow air foil disposed on each side of said fire box, the sides of each of said foils converging upwardly to form a ridge, the side of each foil nearest the fire box diverging upwardly with relation thereto, a connecting duct between said foils extending around the front of the fire box, a connecting duct between one of said foils and the fire box, a smoke outlet from the second foil communicating with the atmosphere and a casing enclosing said fire box, air foils, and connections from which casing warm air can be drawn for house heating purposes.

2. In a furnace of the class described, the combination of a retort having a fire box disposed above same, the sides of said fire box converging steeply in an upward direction to form a ridge, an upwardly tapering hollow air foil on each side of said fire box and spaced therefrom, a smoke outlet connection from the fire box to the interior of one of said foils, a smoke connection between said foils, and a smoke outlet from the second foil to the atmosphere and a casing enclosing said fire box and foils, the uppermost side of said casing converging towards the center of the furnace substantially in parallelism with the outermost sides of the foils and spaced therefrom.

MAX C. RICHARDSON.
